UNITED STATES PATENT OFFICE

2,099,925

SMOKING TUBE

Edmund Bruder, Chicago, Ill.

Application May 9, 1935, Serial No. 20,653

19 Claims. (Cl. 131—22)

This invention relates to improvements in smoking tubes, and one of the objects of the invention is to provide in an improved device of this character, means for filtering the smoke so as to remove a considerable portion of the nicotine therefrom before it reaches the smoker.

A further object is to provide improved means for preventing moisture or saliva from contacting the tobacco.

10 A further object is to provide an improved device of this character in which the tobacco may be inserted in a loose condition or in the form of a cigarette or cartridge, and improved means for automatically advancing the tobacco 15 to the lighted end of the device as the tobacco is consumed.

15 A further object is to provide an improved device of this character which is of a sectional construction, comprising parts detachably secured together, whereby the insertion of the smoking material may be readily accomplished, and whereby the parts of the device may be readily separated to facilitate the cleaning thereof.

To the attainment of these ends and the accomplishment of other new and useful objects as will appear, the invention consists in the features of novelty in substantially the construction, combination and arrangement of the several parts hereinafter more fully described and claimed and 30 shown in the accompanying drawing illustrating this invention, and in which

Figure 1 is a longitudinal sectional view on an enlarged scale, of an improved device of this character constructed in accordance with the 35 principles of this invention.

Figure 2 is a detail sectional view of the cap member.

Figure 3 is a detail view, partly in elevation and partly in section, of a rotatable abutment 40 member for the tobacco.

Figure 4 is a detail sectional view of the end member of the device.

Figure 5 is a detail view, partly in elevation and partly in section, of the body member having 45 associated therewith a plunger.

Figure 6 is a view taken on line 6—6, Figure 2.

Figure 7 is a view taken on line 7—7, Figure 3.

Figure 8 is a view taken on line 8—8, Figure 4.

Figure 9 is a detail view taken on line 9—9,

50 Figure 5, with parts omitted.

Figure 10 is a detail view taken on line 10—10, Figure 5.

Figure 11 is an assembled, detailed sectional view of a portion of the device on an enlarged 55 scale.

Figure 12 is a detailed sectional view on line 12—12, Figure 11.

Referring more particularly to the drawing, the numeral 15 designates generally a body portion which may be constructed of any suitable material and of any desired size and configuration. The ends of the body are recessed as at 16—17 to form a dividing partition 18 having a central opening therethrough, and projecting axially from one end of the body is a tubular member 19 of any desired length and diameter and which is provided with a closed bottom 20. The tubular member 19 may be formed integral with the partition 18 or may be formed separately and attached thereto, and has communication with the opening through the partition 18. This opening is preferably of a diameter somewhat larger than the diameter of the tubular member 19 and the wall of the opening or recess 21 is provided with screw threads, for a purpose to be later described.

The recesses 16 and 17 are respectively provided with screw threads 22—23.

The partition 18 may also be provided on its opposite faces with grooves 25 on one side there- 25 communicating with the recess 17 and openings 26, any number of which may be provided, to extend through the bottoms of the grooves 25 to form communicating passages therebetween.

The numeral 27 designates a hollow end mem- 30 ber which is provided with a body portion having a reduced end 28 having external screw threads 29. The other end 30 of the end member 27 is provided with a closure 31 having a central opening 32 therethrough, and openings 33 are 35 provided in the closure 31 of the member 27 to encompass the opening 32. The end member 27 may be of any desired or suitable length.

Extending across the openings 33 and project- 40 ing respectively beyond the opposite faces of the end wall 31 are scrapers 33a—33b, and these scrapers are of a thickness considerably less than the diameter of the openings 33 so as not to obstruct the openings to any great extent.

The end member is attached to the body mem- 45 ber 15 by causing the threads 29 thereon to engage the threads 22 in the wall of the recess 16, and when assembled, a shoulder 34 formed by the reduced end 28 of the member 27 will abut the end of the body portion 15. The external 50 contour of the member 27 is shaped to conform to the contour of the body member 15.

The numeral 35 designates a stem or mouth piece which may be of any desired size and configuration and is provided with a reduced ex- 55

tremity 36 having external screw threads 37. This extremity 36 is adapted to fit into the recess 19 in the body member 15, so that the threads 37 will engage the threads 23 in the wall of the recess 17. A shoulder 38 formed by the reduced portion 36 of the stem will abut the other end of the body member 15, and if desired, ornamenting bands 39-40 may be provided to cover the joints formed between the body 15 and the 10 end and stem members 27-35.

Within the stem 35 are passages 41, any number of which may be provided. One end of the passages opens through the extremity 42 of the stem, and the other end of the passages 41 has 15 communication with a groove 43 in the other extremity of the stem, and which groove 43 is in alignment, when the parts are assembled, with the groove 25 in the partition 18, so that there will be a communication between the groove 43 20 and the chamber 44 in the end member 27.

The reduced end 36 of the stem member 35 is of such a length that when the shoulder 38 abuts the end of the body member 15, the inner extremity of the stem member will terminate short 25 of the partition 18 in the body member 15 to form a recess or chamber 45 in which is arranged a filter 46 constructed of any suitable material and preferably in the form of a disc, which substantially fills the space between the extremity 30 of the stem member 35 and the proximate face of the partition 18. This filter will extend over the groove 25 in the partition 18 as well as over the groove 43 in the end of the stem member.

Within the tubular member 19 is arranged a 35 plunger 47 to which is connected a stem 48, and to the end of the stem is connected a follower 49 having any desired number of openings 50 therethrough, and the follower 49 is of a diameter to substantially fill the chamber 44 in the 40 end member 27. The periphery of the follower 49 is preferably beveled as at 51 to form a substantially sharp edge 52 which contacts and moves along the wall of the chamber 44 in the end member 27. A nut 53 encompasses the rod 48 and is adapted to be threaded into and seated within the recess 21 in the partition 18 so as to 45 form a guide for the stem 48 and to hold the same centrally positioned.

A spring 54 may be provided in the tubular member 19 between the closed end 20 thereof and the lower end of the plunger 47, and the 50 normal tendency of the spring 54 is to advance the plunger 47 to move the head 49 toward the closed end 31 of the chamber 44 in the end member 27, for a purpose to be described. A projection 55 may be provided on the follower 49, 55 preferably centrally disposed with respect thereto, and to extend therebeyond, which serves as a limiting stop to limit the movement of the follower 49 under the stress of the spring 54, in a manner and for a purpose to be hereinafter described.

The numeral 56 designates an abutment member which is provided with a stem 57, angular in 60 cross section, preferably triangular. The extremity of the stem 57 is formed by reducing a portion thereof to provide a shoulder 58 spaced from the member 56 and a circumferential groove 59 is provided in the stem. This abutment member is placed in position within the chamber 44 of the end member 27 through the open end of the chamber, so that the stem will pass through the opening 32 to such an extent that the groove 59 will be disposed beyond the outer surface of 70

the end wall 31 of the chamber 44 of the end member 27, but in proximity thereto.

Openings 60 pass through the member 56 and any desired number may be provided, but preferably three are employed, one opening being disposed adjacent each face of the triangular portion of the stem 57 and in such position that they may be moved into and out of alignment with the openings 33 in the end 31 of the end member 27. In the upper face of the member 56 10 is an open annular groove 60^a with which the openings 60 communicate.

The numeral 61 designates a cap member which is hollow and is provided with a partition 62 intermediate the ends of the member. The portion of the cap below the partition 62 forms a recess or chamber 63 having a circumferential groove 64 on the inner wall thereof. The portion of the member 61 above the partition 62 forms a chamber 65 and the walls of this chamber may be of any desired configuration and may be flared as shown. A projection 66 extends beyond the partition 62 into the chamber 65 and is preferably centrally located. This projection is hollow and communicates with the chamber 63 through the partition. One portion 67 of the projection 66 is angular in cross section and of such a configuration as to conform to the contour of the stem 57 of the member 56. The lower portion of the projection is recessed as at 68 to 30 form a shoulder 69 and the portion 68 is of a size to receive the shouldered portion 58 of the stem of the abutment member 56, and so that the shoulder 58 will contact with the shoulder 69 of the recessed portion 68.

Openings 70 extend through the partition 62 to form communication between the chamber 65 and the recess or chamber 63 and any desired number of these openings may be provided, but preferably three are shown. A groove 70^a is provided in the lower face of the partition 62 and with these grooves the openings 70 have communication.

When the abutment member 56 is placed in position in the end member 27 with the recess 59 above or beyond the wall of the end 31, a fastening device, such as a C shaped spring 71 is placed within the recess 59 so as to extend beyond the wall of the opening 32 and thereby rotatably secure the abutment member 56 to the end member 27. The openings 33 will then be in registration with the groove 60^a in the outer face of the end wall 31 of the end member 27, and the scrapers 33^b on the wall 31 will project into the groove 60^a.

The cap member 61 is then placed in position by inserting the chamber 63 over the closed end of the end member 27, so that the angular stem 57 of the member 56 will enter the angularly shaped recess 67 in the projection 66 on the cap member 61. The groove 70^a will receive the scrapers 33^a and the openings 33 will be in registration with the groove 70^a. The cap member is then secured to the end member by means of a substantially C shaped spring or wire member 72 which is seated in the groove 64 in the wall of the chamber 63 of the cap member 61, and a circumferential open groove 73 in the outer face of the end 30 of the end member 27.

When the cap member 61 and end member 27 are thus assembled, it will be manifest that the cap member 61 may be rotated with respect to the end member 27 by reason of the fastening spring or member 72 entering the recesses 64 and 73.

As the abutment member 56 is secured to the cap member 61 against rotation with respect thereto, by reason of the angular portion 57 of the stem entering the angularly shaped recess 67 in the end member, it will be manifest that the abutment member 56 will be rotated within the end member 21.

When the cap member 61 and the end member 28 together with the abutment 56 are rotated with respect to the end member 21, the scrapers 33^a and 33^b will be respectively moved in the grooves 70^a in the cap member 61 and 60^a in the wall 31 of the end member 21, with the result that a double ash shaker and agitator 15 coming into direct contact with the tobacco on the inside as well as on the outside of the container will be provided and at the same time the grooves 70^a and 60^a will be automatically maintained clean so as not to interfere with a draft 20 through the openings 70, 33 and 60.

By reason of the triangular shaped stem 57 having the openings 70 adjacent each face thereof, it will be manifest that no matter in what position the stem 57 is inserted in the recess 67, the openings in the member 56 will always register with the respective openings 70 in the partition 62 in the cap member 61.

The product to be smoked, indicated by the reference numeral 74, may be either in the form 30 of loose tobacco, cigarette or cartridge, and if in the form of a cigarette or cartridge, is of a diameter to substantially fill the chamber 44 in the end member 21. To insert the same, the end member with the cap 61 attached thereto, is detached from the body member 15 and the cigarette, cartridge or tobacco is inserted into the chamber 44, after which the end member 21 is secured to the body member 15. After these parts are assembled, the end of the product within the 40 chamber 44 will contact with the follower 49 of the plunger 47 and the follower and plunger will be depressed against the stress of the spring 54.

Inasmuch as the openings in the abutment member 56, partition 62 of the cap member 61 and the openings 33 of the end member 21 may be in alignment, it will be manifest that by applying a lighted match the tobacco will be ignited through these registering openings.

During the smoking operation, the smoke will 50 be drawn through the openings 50 in the follower 49, openings 26 in the partition 18 of the body member, filter 46 and passages 41 in the stem 35, thereby causing a filtration of the smoke and the removal of a considerable portion of the 55 nicotine.

At the same time, the filter 46 will prevent the saliva and moisture from coming into contact with the tobacco.

As the tobacco is consumed, the spring 54 will 60 cause the follower 49 to force the unconsumed tobacco into contact with the abutment member 56, and this operation will continue until all of the tobacco is consumed. The projection 55 contacting with the abutment 56 will limit the 65 movement of the head 49 under the stress of the spring 54.

During the smoking operation, if it is desired 70 to remove any ashes which may accumulate or form at the end of the tobacco adjacent the abutment plate, the latter may be rotated by rotating the cap member 61 with respect to the end member 21, and this will cause the ashes to pass through the registering openings to be discharged through the chamber 65 in the cap 75 member 61.

With this improved construction it will be manifest that a simple and practical device will be provided and a sanitary construction will result, it being possible to separate all of the parts if desired, for the purpose of cleaning, and if desired, the stem 35 may be removed in order to permit of the changing of the filter material 46.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A smoking tube of the character described comprising a body formed of separable sections and embodying a tobacco chamber, said chamber having an end wall provided with openings therethrough, and a freely rotatable element adjacent said wall, said element providing an abutment for the tobacco.

2. A smoking tube of the character described comprising a body formed of separable sections and embodying a tobacco chamber, said chamber having an end wall provided with openings therethrough, a freely rotatable element adjacent said wall, said element providing an abutment for the tobacco, and means tending normally to urge the tobacco against said element.

3. A smoking tube of the character described comprising a body formed of separable sections and embodying a tobacco chamber, said chamber having an end wall provided with openings therethrough, and a freely rotatable element adjacent said wall, said element providing an abutment for the tobacco, said element being disposed within said chamber and provided with openings therethrough adapted to be moved into and out of register with the openings in said wall, as the element is rotated.

4. A smoking tube of the character described comprising a body formed of separable sections and embodying a tobacco chamber, said chamber having an end wall provided with openings therethrough, a freely rotatable element adjacent said wall, said element providing an abutment for the tobacco, a cap member encompassing a portion of said chamber and freely rotatable with respect thereto, and means detachably securing said cap member and said element together.

5. A smoking tube of the character described comprising a body formed of separable sections and embodying a tobacco chamber, said chamber having an end wall provided with openings therethrough, a freely rotatable element adjacent said wall, said element providing an abutment for the tobacco, a cap member encompassing a portion of said chamber and freely rotatable with respect thereto, and means detachably securing said cap member and said element together, said cap member and said element being disposed on opposite sides of said wall and being separably connected together through said wall.

6. A smoking tube of the character described comprising a body formed of separable sections and embodying a tobacco chamber, said chamber having an end wall provided with openings therethrough, a freely rotatable element adjacent said wall, said element providing an abutment for the tobacco, a follower in the chamber, means tending normally to urge the follower towards said wall, said follower being of a diameter only slightly less than the diameter of the chamber, the periphery of the following being shaped so as to

form a fine edge movable along the chamber wall.

7. A smoking tube of the character described comprising a body formed of separable sections and embodying a tobacco chamber, said chamber having an end wall provided with openings therethrough, a freely rotatable element adjacent said wall, said element providing an abutment for the lighted end of the tobacco charge, a stem having a bit at the end, and a filter disposed between said chamber and said bit.

8. A smoking tube formed of a plurality of axially alined sections separably secured together, a tobacco containing chamber in one of the sections, a removable filter between said sections, a follower in the chamber on one side of the filter, a projection on the follower extending through the filter, and means on the other side of the filter and co-operating with said projection for moving the follower, one of said sections constituting a stem.

9. A smoking tube formed of a plurality of axially alined sections separably secured together, one of said sections constituting a stem, a tobacco chamber in one of the sections, an abutment in the chamber disposed between the smoking charge and that end of the said chamber which is remote from the stem end of the chamber, means for urging the tobacco against the abutment, and means for freely rotating said abutment within the chamber and from the outside thereof.

10. A smoking tube formed of a plurality of axially alined sections separably secured together, a tobacco chamber in one of the sections, an abutment in the chamber, means for urging the tobacco against the abutment, and means for freely rotating said abutment within the chamber and from the outside thereof, there being openings leading through a wall of the chamber and through said abutment.

11. A smoking tube embodying a plurality of axially alined sections separably secured together, a tobacco chamber in one of the sections, an abutment member in the chamber, one of said sections and said abutment member being provided one with a stem angular in cross section and the other with a recess conforming in contour with and receiving the stem, and means for detachably securing said abutment member and the last said section together, said abutment being freely rotatable in and from the outside of said chamber.

12. A smoking tube formed of a plurality of axially alined sections separably secured together, a tobacco chamber in one of the sections, an abutment in the chamber, means for urging the tobacco against the abutment, means for freely rotating said abutment within the chamber and from the outside thereof, and means carried by the first recited means and serving as a stop for limiting the movement thereof.

13. A smoking tube of the character described embodying a plurality of axially alined sections, one of the sections constituting a hollow body provided with a partition spaced from the ends thereof, a chambered member detachably secured to the said body on one side of said partition, said chamber having communication with openings through the partition, a stem having smoke passages therethrough and removably secured to said body on the other side of the partition, a filter disposed between the end of said stem and said partition, a follower within said

chamber, and means operating through said partition for advancing the follower.

14. A smoking tube of the character described embodying a plurality of axially alined sections, one of the sections constituting a hollow body provided with a partition spaced from the ends thereof, a chambered member detachably secured to the said body on one side of said partition, said chamber having communication with openings through the partition, a stem having smoke passages therethrough and removably secured to said body on the other side of the partition, a filter disposed between the end of said stem and said partition, a follower within said chamber, means operating through said partition for advancing the follower, an abutment member within the chamber against which tobacco is urged by said follower, and means exterior of said chamber for freely rotating the abutment in the chamber.

15. A smoking tube of the character described embodying a plurality of axially alined sections, one of the sections constituting a hollow body provided with a partition spaced from the ends thereof, a chambered member detachably secured to the said body on one side of said partition, said chamber having communication with openings through the partition, a stem having smoke passages therethrough and removably secured to said body on the other side of the partition, a filter disposed between the end of said stem and said partition, a follower within said chamber, means operating through said partition for advancing the follower, one of said sections constituting a freely rotatable cap member, an abutment within the chamber against which the tobacco is urged by said follower, and means detachably connecting said member and said abutment member through a wall of said chamber.

16. A smoking tube of the character described embodying a plurality of axially alined sections, one of the sections constituting a hollow body provided with a partition spaced from the ends thereof, a chambered member detachably secured to the said body on one side of said partition, said chamber having communication with openings through the partition, a stem having smoke passages therethrough and removably secured to said body on the other side of the partition, a filter disposed between the end of said stem and said partition, a follower within said chamber, a tubular member supported by said partition and extending into said stem member, a plunger in said tubular member, a connection between said plunger and said follower and extending through said partition, and a spring also in said tubular member and operating upon said plunger to advance said follower.

17. A smoking tube of the character described embodying a body having a tobacco chamber therein, there being openings through one wall of the chamber, a rotatable element adjacent said wall providing an abutment for the tobacco, there being openings through said abutment adapted to be moved into and out of register with the openings in said wall, the adjacent faces of said wall and abutment being disposed in close proximity, one of said faces being provided with an annular groove, and a projection extending beyond the other face and projecting into said groove, said projection serving as a scraper movable in the groove as the said element is rotated.

18. A smoking tube of the character described embodying a tobacco chamber having openings through a wall thereof, rotatable elements on op-

posite sides of said wall each having openings adapted to be moved into and out of register with the openings in said wall, means operatively connecting said elements whereby one will be rotated by the rotation of the other, one of each pair of proximate faces of the wall and the respective elements being provided with an annular groove with which the respective openings communicate, and a projection carried by the other face of each pair and projecting into the respective grooves to serve as a scraper for the groove when the elements are rotated with respect to said wall.

19. A smoking tube embodying a body portion and end sections detachably secured together, a tobacco containing chamber in one of the end sections, the other end section constituting a stem, a removable filter between the said body portion and one of said end sections, a follower in said chamber, and means for urging the follower forwardly in the said chamber, the said means being disposed outside of the said chamber.

EDMUND BRUDER.

10
